UNITED STATES PATENT OFFICE.

COLVIN L. JOHNSON, OF ST. LOUIS, MISSOURI, ASSIGNOR, BY MESNE ASSIGNMENTS, TO JOHNSON AUTOMOBILE LOCK CO., OF ST. LOUIS, MISSOURI, A CORPORATION OF MISSOURI.

TRANSMISSION LOCK.

Application filed November 24, 1926, Serial No. 150,424. Renewed October 6, 1928.

This invention relates to transmission locks and more particularly to improved means for enabling the convenient assembly and preventing the unauthorized removal thereof.

5 One object of the present invention is to simplify the construction and improve the operation of devices of the character mentioned.

Another object is to provide means whereby 10 a transmission lock or the like may be readily assembled to prevent the unauthorized removal thereof.

A further object is to provide novel means to prevent the removal of the transmission 15 lock assembly when in its inoperative position.

Other objects and advantages will appear from the following description of an illustrated embodiment of the present invention.

20 In the drawings:

Figure 1 is a sectional view of a transmission lock embodying features of the present invention.

Figure 2 is a sectional view taken substantially along line II—II of Figure 1.

Figure 3 is a sectional view taken substantially along line III—III of Figure 1.

Figure 4 is a sectional view taken substantially along line IV—IV of Figure 1.

30 The structure selected for illustration is shown associated with a transmission housing 10 of standard construction, wherein the usual gear shifting rods 11 are slidably mounted, they being provided with confronting arcuate recessed portions 12 for selectively receiving a lock plunger 13 to be hereinafter described. The housing 10 is, in this instance, provided with a boss 10' which is centrally bored to receive a barrel 14 which is brazed 35 or otherwise secured to a casing 15 adapted to receive a key-operated tumbler lock 16 of standard construction. The barrel 14 is provided with an axial bore 17 for a portion of the length thereof, it terminating in an enlarged passage 18 extending axially of the bore 17 in the adjacent portions of the barrel 40 and casings 14 and 15, respectively.

45 The plunger 13 is slidably mounted in the bore 17 of the barrel 14 with the enlarged shank 19 thereof confined within the passage 18 to project exteriorly of the casing 15, it being normally urged outwardly by the action of a spiral spring 20, which encircles the plunger 13 within the passage 18 intermediate

the shoulders defined by the reduced bore 17 55 and the shank 19.

A locking pin 21 of standard construction is operatively connected to the tumbler lock 16 which controls its sliding movement in a passage 22, disposed normal to the shank 19 60 in the casing 15. The pin 21 is normally urged in the direction of the shank 19 to contact therewith by means of a spring 23 positioned within the passage 22 intermediate the closed end thereof and an extremity of the pin 21, 65 the other extremity thereof being lodged in a recess 24 provided in the shank 19 to prevent retraction of the plunger 13 when it is moved to its extreme downward position in locking engagement with the gear shifting 70 rods 11, supra. The plunger 13 is released from locking engagement with the gear shifting rods 11 by manipulating a key 25 individual to the tumbler 16 whereby the pin 21 is retracted against the action of the spring 23 75 to permit the plunger 13 to move outwardly owing to the spring 20 positioned within the passage 18.

In order to effectively and conveniently lock the barrel 14 to the transmission housing 80 10, simple means are provided to enable the convenient assembly thereof, as well as to prevent unauthorized removal. The means, in this instance, comprise a plurality of radially projecting apertures 26 and 27 which communicate with the bore 17 of the barrel 14 to permit the insertion of pins 28 and 29, respectively, therein, to assume a position within the apertures 26 and 27, the pins having the shanks thereof projecting exteriorly of 90 the barrel 14 with the enlarged heads 30 thereof engaging an annular ring 31 projecting within the apertures intermediate the ends thereof. The exteriorly projecting shanks of the pins 28 and 29 engage correspondingly spaced apertures 32 provided in the transmission housing 10 adjacent the barrel 14 whereby removal of the latter is rendered impossible.

95 The pins 28 and 29 are retained within their respective apertures by means of the plunger 13 which prevents displacement thereof in all positions of the latter, since its movement is limited between the limits defined by the recess 24 and a slot 33 communicating therewith. As shown, the slot 33 is of less depth 100 than the recess 24, so as only to permit movement of the plunger when the locking pin 21

is retracted by the key 25 to its innermost position which permits the extremity of the pin to project within the slot 33 at all times. To enable the removal of the plunger 13 and the parts associated therewith, a passage 34 is provided in the shank 19 to communicate with the slot 33 so that when the plunger is in its normally retracted position, the passage 34 will be in alignment with the locking pin 21 to which access is gained by means of a passage 35 provided in the casing 15 in communication with the passage 18 and in alignment with the passage 22.

With the arrangement of parts above described, it will be apparent that the plunger 13 may be pressed downwardly against the action of the spring 20 to engage the recess 12 in the shifting rod 11 when the latter is in a predetermined position, thereby locking the rods 11 against movement. In this position, the recess 24 confronts the locking pin 21 which is lodged therein by means of the spring 23. The plunger 13 is released by manipulating the key 25 to retract the pin 21 sufficiently to permit upward movement of the plunger 13, the movement of which is limited by the shoulder defined by the slot 33, adapted to engage the extremity of the locking pin 21 when the latter is in its retracted position. Thus the pins 28 and 29 engage the transmission housing 10 at all times to prevent the unauthorized removal of the transmission lock, since the pins 28 and 29 can only be removed by withdrawing the plunger 13 from the barrel 14, this being only possible when the plunger 13 assumes its normally unlocked position. With the plunger 13 in its unlocked position, the passage 34 in the shank 19 communicates with the passage 35 in the casing 15 to permit a nail or similar instrument to be inserted therein for retracting the locking pins 21 within the passage 22 until it is entirely removed from the passage 18.

I am aware that many changes may be made, and numerous details of the construction may be varied through a wide range without departing from the principles of this invention, and I therefore do not purpose limiting the patent granted hereon, otherwise than necessitated by the prior art.

I claim as my invention:

1. In a transmission lock, a barrel having an axial bore, a key operated transmission locking plunger slidable in said bore, barrel locking means insertable through said bore, and means for preventing rotation and for limiting the axial movement of said plunger to maintain said barrel locking means in operative position.

2. In a transmission lock, a barrel having an axial bore, a key operated transmission locking plunger slidable in said bore, barrel locking means insertable through said bore, and means for limiting the movement of said

plunger to permanently maintain said barrel locking means in operative position, said barrel locking means comprising a radially projecting pin, said plunger having a transverse passageway adapted to be aligned with an opening in said barrel whereby an instrument may be inserted in said passageway to unlock said plunger so as to permit of its removal from said barrel.

3. The combination with a transmission housing, gear shift means in said housing, a lock barrel removably associated with said housing, a plunger in said barrel engageable with said gear shift means, and locking means associated with said barrel and housing effective to prevent unauthorized removal as well as rotation of said barrel.

4. The combination with a transmission housing, of gear shift means in said housing, a non-rotatable lock barrel projecting in said housing, a plunger slidable in said barrel for locking engagement with said gear shift means, there being aligned apertures in said barrel and housing, and a pin slidable in said apertures to lock said barrel against rotation and to said housing, said plunger preventing retraction of said pin.

5. The combination with a transmission housing, of gear shift means in said housing, a lock barrel projecting in said housing, a plunger slidable in said barrel for locking engagement with said gear shift means, there being aligned apertures in said barrel and housing, a pin slidable in said apertures to lock said barrel to said housing, said plunger preventing retraction of said pin, and means for limiting the movement of said plunger to an extent sufficient to maintain said plunger in engagement with said pin.

6. The combination with a transmission housing, of gear shifting means therein, a lock barrel associated with said housing, means for locking said barrel to said housing, a plunger in said barrel engageable with said gear shift means in a predetermined position, and means for limiting the movement of said plunger in said barrel, said limiting means including a key operated locking pin, there being a recessed seat in said plunger with a communicating slot for receiving said locking pin.

7. The combination with a transmission housing, of gear shifting means therein, a lock barrel associated with said housing, means for locking said barrel to said housing, a plunger in said barrel engageable with said gear shift means in a predetermined position, means for limiting the movement of said plunger in said barrel, said limiting means including a key operated locking pin, there being a recessed seat in said plunger with a communicating slot for receiving said locking pin, and radially extending, exteriorly projecting pins in said barrel to engage said housing, said pins being irremovable

within the limited movement of said plunger.

8. The combination with a housing, of a locking barrel, a plunger movable therein, a key operated locking pin engaging said plunger in a predetermined position for preventing movement thereof, said locking pin being effective to limit the movement of said plunger in a retracted position, and means projecting exteriorly of said barrel for locking said barrel to said housing, said exteriorly projecting means being irremovable within the limited movement of said plunger.

9. In combination with a transmission including gear shift means and a housing, a

lock barrel associated with said housing, a plunger in said barrel arranged for engagement with said gear shift means, and locking means for said plunger in said barrel including a bolt in a recess in said barrel arranged so as to project into a recess in said plunger, said barrel having an opening in alignment with said bolt recess and said plunger having a transverse passageway arranged for alignment with said bolt recess and said opening.

In testimony whereof I have hereunto subscribed my name.

COLVIN L. JOHNSON.
